ROTARY PRINTING PRESS

Curtis S. Crafts and Charles Alonzo Harless, Oak Park, Ill., assignors to The Goss Printing Press Company, Chicago, Ill., a corporation of Illinois

Application September 13, 1934, Serial No. 743,818

12 Claims. (Cl. 101—153)

The invention relates to new and useful improvements in rotary printing presses, and in certain of its features more particularly to improvements in bearings, aligning and registering means for removable and replaceable rotogravure cylinders, including wear compensating means, and demountable, and replaceable wear-compensating driving means for such cylinders.

Objects and advantages of the invention will be set forth in part hereinafter and in part will be obvious herefrom, or may be learned by practice with the invention, the same being realized and attained by means of the instrumentalities and combinations pointed out in the appended 15 claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a sectional view of shaft bearing devices and endwise registering means for a rotogravure cylinder, taken on the line 1—1 of Fig. 3;

Fig. 2 is a section taken on the line 2—2 of Fig. 3, with certain parts in elevation;

Fig. 3 is a full elevation looking at Figs. 1 and 2 from the right;

Fig. 4 is a section of the shaft bearing means and the driving means for the opposite end of the cylinder, and is taken on the line 4—4 of Fig. 5;

Fig. 5 is an elevation, with parts in section and parts broken away, looking at Fig. 4 from the left;

Fig. 6 is a detached elevation, with parts in section and parts broken away, of the driving gear and attached parts; and

Fig. 7 is a detached detail of the taper gear engaging cap shown in Figs. 4 and 5.

The present invention in many of its features is especially directed to improvements in rotogravure printing presses, and in one of its main aspects the invention provides mounting and journal supports which are absolutely rigid when in place, which will maintain accurate alignment of the shaft, will not lose effective and accurate fit by wear due to recurrent removal and replacement, and which are nevertheless easily and rapidly removable and replaceable to meet the requirement of dismounting the rotogravure cylinders from and re-inserting them in the press

for each press edition. The invention in another of its important features is directed to improved means for effecting endwise registration of the cylinder in the press, such means being simple, sturdy and accurate, and likewise capacitated to operate in connection with the cylinder mounting provided by the invention. In another of its main features, the invention provides driving means for the cylinder especially adapted to be detached from and attached to the cylinder shaft at the recurrent removals and insertions of the cylinder, the detachment and attachment of the drive being easy and simple, and the driving means always maintaining true with the shaft and automatically compensating for the abnormal wear caused by the recurrent dismounting and remounting of the drive.

In our present preferred embodiment, considering its general features, the journals for the printing cylinder shafts are mounted in tapered, and preferably conical supports which fit into correspondingly tapered openings in the press frame, the tapered members being accurately and powerfully moved longitudinally to bring them into uniform and accurate position on the press frame and with respect to each other to always maintain a close and accurate fit in the press frame and like alignment for the ends of the cylinder shaft. Cooperating therewith are means for the quick and easy insertion and removal of the bearing and alining means both with respect to the cylinder shaft and to facilitate the removal from and the reinsertion in the press of the printing cylinder.

In accordance with our invention, the longitudinal or axial registering means for the cylinder is of simple and sturdy construction, affording precise registration of the cylinder, the mechanism being quickly and readily movable into and out of operative relation with the cylinder shaft to meet the need for quick and simple removal and reinsertion of the printing cylinder and of the bearing members for the cylinder shaft. In the present embodiment the registering means engages the end of the cylinder shaft, and screw-threaded means operate to accurately register the cylinder, the registering means then being locked in position. This mechanism is easily and quickly moved out of operative relation with the cylinder and swung to one side for the removal and reinsertion of the cylinder bearing members and of the cylinder itself.

In the embodied driving means, generally considered, a gear having an elongated hub is attachable to the cylinder shaft by feather keys,

and the gear hub and shaft are likewise provided with relatively movable conical clamping members, which clamp the gear firmly to the shaft with accuracy and security irrespective of wear 5 in the hub, the shaft or the keys, due to frequent removal and replacement. In accordance with one feature of the invention, the cylinder shaft ends are reversible or interchangeable and adapted to cooperate with either of the mechanisms 10 described.

It will be understood that the foregoing general description, and the succeeding detailed description as well, are exemplary and illustrative but not restrictive of the invention.

15 Referring now in detail to the embodiment of the invention illustrated by way of example in the accompanying drawings, 1 and 2 are the side frames of the press. These side frames are provided with aligned recessed openings 5 through 20 which the shaft ends pass as the rotogravure cylinder is inserted in position in the press for printing and removed from the press to change the design. In the embodied form of our novel bearing or journal means for the shaft ends of the 25 rotogravure cylinder, the recesses 5 open into enlarged tapered openings 3 and 4 in the press frames, these openings being preferably of conoid or truncated cone form, the taper decreasing inwardly. The rotogravure cylinder is indicated 30 by 8 and its shaft ends 9 and 10 are preferably interchangeable between the drive and the side lay mechanisms.

The journal-supporting mountings or bearing members 14 (Figs. 1, 2, and 4) are of the same 35 shape and size as the press frame openings 3 and 4 and accurately fit within the illustrated conoid openings 3 and 4 in the side frames of the press. They are moved into tight fit in these openings so as to fit accurately and to always center the 40 shaft, notwithstanding wear incident to the frequent removals and replacements of the cylinder. The embodied means for moving the bearing members 14 into and out of tight fitting, centered and aligned relation with respect to the corresponding openings in the press frames, and to hold them firmly in said relation, comprises (Figs. 2 and 3) flanges 15 and 16 extending outwardly from an annular member 17 which is the outer part of the bearing member 14 and is connected 45 to the inner part by screws 18. Cooperating with the diametrically-disposed flanges 15 and 16 are corresponding slotted nuts 19 and 20, the flanges extending into the slots in the nuts, these nuts being of U-shape, and working in correspondingly-shaped recesses 21 and 22 in the 50 press frame so that the nuts are free to move longitudinally, but are held against rotation as their bolts are turned. The nuts are mounted respectively on stud bolts 23 and 24 between the nut 55 heads and collars 25 and 26, pinned to the bolts, whereby the nuts move longitudinally with the bolts, the bolts being threaded into the press frame. Thus, by turning the bolts 23 and 24 the inwardly tapered members 14 are pressed powerfully and accurately into the correspondingly 60 shaped and sized openings in the press frame, and the shaft bearings are accurately centered and firmly held. By turning the bolts in the opposite direction, the bearing members 14 may 65 be quickly and powerfully moved outwardly out of the close contact with the openings 3 and 4 in the press frame.

70 Means are provided for disengaging the shaft bearing members 14 from the slotted nuts 20 and 75 bolts 24, preparatory to removing the bearing

members from the shaft ends, and also for re-engaging them after the bearing member is replaced on the cylinder shaft. As embodied, said means comprises (Figs. 1, 3, and 4) a pair of handles 29 and 30, diametrically disposed and attached to 5 the plate 17 by screws 28. By grasping the handles 29 and 30, the pressman rotates the bearing member 14 sufficiently to clear the flanges 15 and 16 from their respective nuts 19 and 20, as shown in dotted lines in Fig. 3, the flanges moving 10 in corresponding slots 31 and 32 in the press frame. The bearing member is then free and may be slid along and off from the cylinder shaft.

15 The journal bearings for the cylinder shafts 9 and 10 (Figs. 1 and 4) are mounted within the bearing members 14, and as embodied, roller bearings are provided, having a long inner race 40 shrunk on a diminished shoulder portion of the shaft, the inner edge of the race abutting on a shoulder 42 formed on the shaft. The outer 20 flanged race 43 is mounted within the member 14, its inner flanged face abutting on a shoulder 44 formed on the interior of member 14. Oil seals are provided and on the inner side, as embodied, a flexible collar 45 is held fast to the shaft, and forms a seal thereabout, within a recess in the inner face of the conoidal member 14, and this inner recess is closed by an annular plate 46 encircling the cylinder shaft and fastened to the inner face of member 14 by screws 47. The oil seal on the outer side is formed by an annular groove between two flanges 48 and 50 formed on the inner face of the plate 17, the inner flange abutting circumferentially upon the bearing race 40, and the outer flange abutting the outer face 30 of the outer flange 51 of the outer race 48.

35 The embodied means for effecting registration of the rotogravure cylinder (Figs. 1, 2, and 3) is capacitated to move the cylinder axially in its bearings by screw-threaded devices, and to lock 40 the parts in the desired registered position. The entire mechanism is also movable, by swinging about its shaft, away from the cylinder shaft to permit the removal of the bearing member 14 from the shaft. Said embodiment comprises a 45 deep-groove double-roll ball bearing 61, which takes both a radial and a thrust load. The inner race 62 of this bearing is mounted on a cylindrical sleeve 63 and abuts against the inner enlarged or flange portion 65 of the sleeve. This enlarged 50 end of the sleeve fits into a cylindrical recess formed concentrically in the end of the shaft 9 and 10. A cap screw 66 passes through the sleeve 63 into threaded engagement at 67 with the cylinder shaft, the cylindrical portion 64 of the cap screw head abutting on the outer side of the inner ball race 62, thus holding the sleeve and inner race fixed to the shaft. The outer race 68 of the ball bearing is mounted in a cylindrical recess in the head 75 of the side lay arm 74, the 55 recess being closed by an annular cap 76, which encircles the head of the cap screw 66 and is fastened to the head 75 by screws 77. The hollow part-cylindrical head 78 of the side lay bracket encloses the end of the cylinder shaft, and is 60 open on one side to clear the cylinder shaft when the arm 74 and the parts mounted thereon are swung away from the cylinder shaft.

65 The arm 74 is mounted to be moved laterally to register the cylinder and to move angularly 70 into and out of operative relation with the cylinder shaft. As embodied, the hub 81 of the arm 74 is mounted on a shaft 82, which shaft is rotatably mounted at 84 in the side frame 1 of the press. The outer end of shaft 82 is jour- 75

nalled in a fixed bracket 85, which bracket is fastened to the press side frame by bolts 86. A crank 87 is fixed to the outer end of shaft 82. The hub 81 has internal screw-threaded engagement with a screw thread on shaft 82, as shown at 88, and cooperating therewith are means for locking arms 74 and shaft 82 together in the proper registration position for the press cylinder. For this purpose, as embodied, the outer 10 portion 91 of sleeve 81 is angularly slotted, and a locking bolt 92 is loose in lugs 93 and 94 at either side of the longitudinal part of slot 91. A handled nut 95 is threaded onto the outer end of screw 92, and by turning the handle a part 15 turn the hub and shaft may be locked together or may be loosened so that the hub 81 and arm 74 may be screw fed along the shaft. The member 96 formed on hub 81 coacts with a face 97 on the bracket 85 to hold the arm 74 in either operating 20 or retracted position, shown in full and dotted lines in Fig. 3.

Referring now to the present preferred embodiment of the drive for the printing cylinder, as previously stated, the two cylinder shaft ends 25 are interchangeable, and they are accordingly so shown. In said embodiment (Figs. 4-7) a gear 101 is mounted on the drive end of the shaft, its elongated hub 102 being connected to the shaft by feather keys 103, 104. The inner and outer 30 ends of the bore of hub 102 are beveled or coned, as shown at 105 and 106. When the hub slips on to the shaft, the inner bevel 106 engages with a beveled ring 109 fixed on the cylinder shaft, and abutting on the journal bearing member 40 35 and the shoulder in the shaft. A resilient slotted cap 111 is mounted loosely with the gear 101, and is adapted to inclose the outer end of the cylinder shaft. The outer face of the inner edge of the cap is of outwardly enlarged conical form as 40 shown at 115. The part 115 is adapted to engage with the outer bevel surface 105 of the hub bore of the gear wheel. The cap 111 is held loosely to the hub by means of a flanged ring 116, bolted to the hub by bolts 117, the flange 118 being 45 outside of and overhanging the shoulder 119 of the cap 111. A tap bolt 121 passes through a central aperture in the cap 111 and is screw-threaded into the end of the cylinder shaft. There is a washer 122 between the bolt-head and the cap, 50 and a collar 123 is pinned to the bolt within the cap, the collar passing freely into a concentric cylindrical recess in the end of the cylinder shaft. When the bolt is screwed in, the cap 111 is moved 55 inwardly, and the hub is clamped firmly between the beveled part 115 of cap 111 and the bevel ring 109 fixed on the cylinder shaft, and thus the gear is firmly fixed to the shaft irrespective of wear 60 in the hub and the shaft due to the recurrent removal and replacement of the drive and the cylinder.

The invention in its broader aspects is not limited to the specific mechanisms shown and described but departures may be made therefrom within the scope of the accompanying claims 65 without departing from the principles of the invention and without sacrificing its chief advantages.

What we claim is:

1. A rotary intaglio press including in combination a side frame having a recessed and slotted opening for removal of the rotogravure cylinder, said opening terminating in a tapered bearing-receiving opening, a tapered shaft-bearing member 70 slidable on the shaft of corresponding size and shape to the tapered frame opening, and

means for forcing the tapered face of the bearing member into tight centered engagement with the tapered face of the frame opening.

2. A rotary intaglio press including in combination two side frame members having respectively recessed and slotted openings for removal of a rotogravure cylinder, each of said openings terminating in a tapered bearing-receiving opening, two tapered shaft-bearing members of corresponding size and shape with the tapered frame openings axially movable on the shaft, and means for forcing the tapered faces of the bearing members into tight centered engagement with the tapered faces of the corresponding frame openings to bring the ends of the cylinder shaft into accurate alinement. 15

3. A rotary intaglio press including in combination two side frame members having respectively alined recessed and slotted openings for removal of a rotogravure cylinder, each of said openings terminating in a tapered bearing-receiving opening decreasing inwardly, two tapered shaft-bearing members adapted to receive the two ends of the cylinder shaft for sliding and rotary movement and of corresponding size and shape with the tapered frame openings, and means for forcing the bearing members when about the cylinder shafts inwardly into tight centered engagement with the tapered faces of the corresponding frame openings to bring the ends 30 of the cylinder shaft into accurate alinement. 25

4. A rotary intaglio press including in combination a side frame member having a tapered circular opening communicating with an open-ended slot, a tapered circular shaft-bearing member 35 slidable on the shaft, and means equipped with screw threads for forcing the tapered circular surface of the shaft-bearing member into tight centered engagement with the corresponding surface of the frame opening while permitting sliding movement of the shaft in the bearing. 40

5. A rotary intaglio press including in combination a side frame member having a tapered circular opening communicating with an open-ended slot, a tapered circular shaft-bearing member 45 slidable on the shaft, and means for forcing the tapered circular bearing member axially into tight centered engagement with the corresponding surface of the frame opening to aline the shaft bearing while permitting sliding movement of the shaft 50 in the bearing.

6. A rotary intaglio press including in combination a side frame member having a tapered circular opening communicating with an open-ended slot, a tapered circular shaft-bearing member 55 slidable on the shaft, and means equipped with screw threads for forcing the tapered circular bearing member axially into tight centered engagement with the corresponding surface of the frame opening to aline the shaft bearing 60 while permitting sliding movement of the shaft in the bearing.

7. A rotary intaglio press including in combination a side frame having a tapered circular opening communicating with an open-ended slot, 65 a tapered circular shaft-bearing member slidable on the shaft, means for forcing the tapered circular bearing member axially into tight centered engagement with the corresponding surface of the frame opening to align the shaft bearing while 70 permitting sliding movement of the shaft in the bearing, and means for moving the tapered circular bearing member angularly to permit removal thereof from the press frame.

8. A rotary printing press including in com- 75

- bination a frame having a slotted aperture to receive a shaft bearing, a design cylinder, a radial shaft bearing in said frame aperture and removable therefrom to permit lateral removal of the design cylinder by movement of its shaft ends through said aperture, a thrust bearing at the end of said shaft, a support for the thrust bearing and means for removing said support and thrust bearing laterally to permit lateral removal of the design cylinder.
9. A rotary printing press including in combination a frame having a slotted aperture to receive a shaft bearing, a design cylinder, a radial shaft bearing in said frame aperture and removable therefrom to permit lateral removal of the design cylinder by movement of its shaft ends through said aperture, a thrust bearing having a member connectable to and disconnectable from said shaft, a support for the thrust bearing and means for removing said support and thrust bearing laterally to permit lateral removal of the design cylinder.
10. A rotary printing press including in combination a frame having a slotted aperture to receive a shaft bearing, a design cylinder, a radial shaft bearing in said frame aperture and removable therefrom to permit lateral removal of the design cylinder by movement of its shaft ends through said aperture, a thrust bearing at the end of said shaft, a screw-threaded connection between said thrust bearing and said shaft, a support for said thrust bearing, a pivotal mounting for said support about which it is movable to permit endwise removal of the design cylinder.
11. A rotary printing press including in combination a frame having a slotted aperture to receive a shaft bearing, a design cylinder, a radial shaft bearing in said frame aperture and removable therefrom to permit lateral removal of the design cylinder by movement of its shaft ends through said aperture, a thrust bearing at the end of said shaft, a screw-threaded connection between said thrust bearing and said shaft, a support for said thrust bearing, a pivotal mounting for said support about which it is movable to permit endwise removal of the design cylinder.
12. A rotary printing press including in combination a frame having a slotted aperture to receive a shaft bearing, a design cylinder, a radial shaft bearing in said frame aperture and removable therefrom to permit lateral removal of the design cylinder by movement of its shaft ends through said aperture, a thrust bearing at the end of said shaft, a support for the thrust bearing and means for removing said support and thrust bearing laterally to permit lateral removal of the design cylinder and means for effecting axial adjustment of said thrust bearing.
